UNITED STATES PATENT OFFICE.

HAROLD W. SHONNARD, OF UPPER MONTCLAIR, NEW JERSEY, ASSIGNOR TO CRUCIBLE STEEL COMPANY OF AMERICA, OF PITTSBURGH, PENNSYLVANIA, A CORPORATION OF NEW JERSEY.

GYROSCOPICALLY-CONTROLLED TORPEDO.

1,296,334.

Specification of Letters Patent.

Patented Mar. 4, 1919.

Application filed August 30, 1917. Serial No. 188,955.

To all whom it may concern:

Be it known that I, HAROLD W. SHONNARD, residing at Upper Montclair, in the county of Essex and State of New Jersey, 5 a citizen of the United States, have invented or discovered certain new and useful Improvements in Gyroscopically - Controlled Torpedoes, of which improvements the following is a specification.

10 My invention relates to gyroscopically controlled automobile torpedoes of the general character shown in my U. S. Patents Nos. 1,035,647 and 1,163,606. In the former I have disclosed certain improvements in 15 methods of fire control, whereby the final ejecting impulse for launching torpedoes is initiated after beginning the spinning of the gyroscope, the releasing of the gyroscope being effected before the torpedo is freed 20 from the directing influence of the launching apparatus; while in the second named patent I have disclosed improved mechanism for carrying out the method of the first patent when the torpedo is controlled 25 by an electric motor gyroscope.

The object of my present invention is to further improve the mechanism disclosed in both named patents to carry out the method of the earlier. A more specific object is to 30 provide improved mechanism whereby the gyroscope may be released either by and upon the initial movement of the torpedo as it leaves the launching apparatus, or at any desired time prior to such movement.

35 In the accompanying sheets of drawings, which form part of my specification, I have illustrated the preferred embodiment of my invention. Figure 1 is a central longitudinal vertical sectional view of a section of a 40 torpedo afterbody, showing in elevation and partly in section the gyroscope and its lock and lock-controlling mechanism; Fig. 2 a transverse sectional view taken on the line II—II Fig. 1, the gyroscope and parts im- 45 mediately connected thereto being shown in elevation; Fig. 3 an enlarged detail sectional view taken on the line III—III, Fig. 2; and Fig. 4 a face view of the mechanism shown in Fig. 3, the plane of view being in- 50 dicated by the line IV—IV.

As far as some features of my invention are concerned, any desired type of gyroscope may be used, although I preferably employ an electric motor gyroscope, which, 55 as shown herein, may be of the same gen-

eral construction as that shown and described in my afore-mentioned Patent No. 1,163,606, and comprising a rotor and outer gimbal. The outer gimbal is formed by the gyroscope housing 3, and the entire 60 gyroscope suitably mounted within a casing 12 secured to the shell 1 of the torpedo. Also, as shown in such patent, the member movable to and from a position for locking the gyroscope is preferably a reciprocatory 65 or slide member 76, provided with a locking pin 78 adapted to enter a suitable pocket or recess in the combined casing and outer gimbal 3 of the gyroscope. As in such patent, the movement of the locking member 70 in both directions is preferably effected by the rotation of a shaft 90 provided with a pinion 89 meshing with a second pinion 86, which, in turn meshes with a rack 85 formed on the locking member 76. For moving the 75 member 76 to a position to lock the gyroscope there is provided a shaft 91 having at its outer end a wrench head 94, for engagement at the exterior of the torpedo, and at its inner end a pinion 92 meshing 80 with a pinion 93 secured to the shaft 90. Thus an operator may turn the shaft 91 with one hand while with the other hand he manipulates the gyroscope to bring it to the proper position to be engaged by the 85 locking pin.

In the foregoing description of the gyroscope, locking member and connections for moving the latter, the same numerals have been used as appear on Fig. 6 of Patent 90 No. 1,163,606. Hence, such details of construction as are not fully shown herein may be readily understood by referring to this patent.

For unlocking the gyroscope by and upon its movement from the launching mechanism, which in most instances is a launching tube of well known construction, the rotary shaft 90 may be provided with an arm 2 pivotally connected to a link 4. This link 100 95 may, by means of a starting latch 5, connected to such link by a rod 6 and bell crank lever 7, be raised to turn the shaft 90, the starting latch being engaged by a detent provided for the purpose on the inside of the launching tube in a manner well understood in the art.

For turning the shaft 90 to unlock the gyroscope independently of or prior to the movement of the torpedo, there is provided 110

within the torpedo a motor mechanism (preferably a spring motor) so connected to such shaft that it may be set without rotating the shaft, and also so constructed that the shaft may be turned by the above described starting latch independently of the operation of the motor mechanism.

In the illustrative embodiment of my invention, two sets of mechanism are provided for this purpose, one located on each side of the torpedo. Since both sets are similar in construction, they being provided so that the torpedo may be launched from either a right or left hand tube, the description of the mechanism will be confined to that shown on the right side of Fig. 2. The shaft 90 has rotatably mounted thereon a pinion 8 provided with a slot 9 adapted to receive a pin 10 formed on the outer end 10 of an arm 11 secured to such shaft. By thus connecting the pinion to the shaft either member may move independently of the other to an extent determined by the length of the slot 9. The spring motor comprises 25 a rotary shaft 13 provided at its outer end with a wrench head 14 and at its inner end with a pinion 15 meshing with the pinion 8, and further provided with an arm 16 connected to one end of a spring 17 which is 30 properly secured at its outer end to a fixed post 18.

Means are provided to lock the spring motor when set, and for releasing such lock by a member operable from the exterior of the torpedo. While various specific constructions may be provided for these purposes, the locking of the spring motor is preferably effected by means of a sliding bar 19 provided on one side with a rack 40 meshing with pinion 8, the bar being held in the position indicated in Figs. 3 and 4 by means of a spring-pressed pawl 20 engaging a detent in the form of a groove 21 in another face of the bar. It will be seen 45 that the spring motor mechanism may be brought to the locked position thus shown and described without turning the shaft 90, and when in such position the shaft 90 may, by turning the shaft 91, be easily rotated 50 to cause the locking pin to properly engage the gyroscope. That is to say, the locking of the gyroscope may be effected by the rotation of the shaft 91, the shaft 90 being unresisted by the spring motor. For releasing 55 the spring motor there is provided a reciprocating spring-pressed button 22 movable from the exterior of the torpedo, and in such movement adapted to trip the pawl 20. The movement of this button may be 60 advantageously effected by the mechanism shown and described in my application Serial No. 188,956, filed of even date herewith, or other mechanism may be provided for this purpose.

65 The spring motor mechanism is prefer-

ably mounted partly adjacent to, and partly upon, a closure member 23 for an opening in the shell of a torpedo, such member also carrying contactors 24 for closing a circuit through the electric motor gyroscope to effect its spinning. As shown herein, the button 22 is mounted on this closure and the electrical contacts are arranged substantially the same as shown and described in my before mentioned Patent No. 1,163,606. However, in the present construction, the outer ends of the contactors are rounded so as to insure good electrical contact with the mechanism of the launching tube for closing the circuit through them. 80

In operation the motor mechanism is first set by turning the shaft 13 until the rack bar 19 is engaged and locked by the pawl 20. The shaft 90 may then be easily turned by means of the shaft 91 to lock the gyroscope. 85 When the torpedo is launched the gyroscope may be unlocked either by the latch 5 or by pressing the button 22. The unlocking by the latch 5 is effected by and upon the initial movement of the torpedo, whereas the unlocking by the pressing of the button 22 may be effected before the torpedo is launched and at such time as the longitudinal axis of the torpedo is pointing in the exact position to cause the gyroscope to properly guide the 90 torpedo on its desired course. When the button 22 is pressed to release the bar 19, the pinion 8 is turned by the pinion 15 impelled by the spring 17, the shaft 90 being turned by the arm 11 which is engaged by 100 the end of the slot 9 formed in pinion 8.

From the foregoing it will be seen that I have provided a construction which is simple and effective, and whereby the unlocking of the gyroscope may be accomplished in 105 two specific manners following the method disclosed in my before mentioned Patent No. 1,035,647.

According to the provisions of the patent statute, I have described the principle and operation of my invention together with the construction which I now consider to be the best embodiment thereof. However, I desire to have it understood that, within the scope of the appended claims, my invention 110 may be practised with other forms of construction than that particularly shown and described.

I claim as my invention:

1. In a gyroscopically controlled torpedo, 120 the combination with a gyroscope, of a member movable to and from a position to lock said gyroscope, spring-impelled mechanism for releasing the locking member, means for moving said member to locking position, and means independent of said last named means for setting said lock-releasing mechanism. 125

2. In a gyroscopically controlled torpedo, 130 the combination with a gyroscope, of a member movable to and from a position to lock

said gyroscope, a rotary member for controlling said locking member, means for turning said rotary member in one direction to move said locking member to locking 5 position, and spring impelled mechanism for turning said rotary member in the opposite direction, and means independent of said rotary-member turning-means for setting said spring impelled mechanism.

10 3. In a gyroscopically controlled torpedo, the combination with a gyroscope, of a member movable to and from a position to lock said gyroscope, a spring motor, connections between said motor and locking member for 15 releasing the latter, means operable independently of the movement of said gyroscope locking member for setting and locking said spring motor, and means operable from the exterior of the torpedo for releasing 20 said spring motor locking means.

4. In a gyroscopically controlled torpedo, the combination with a gyroscope, of a member movable to and from a position to lock said gyroscope, means including a rotary 25 shaft for controlling said locking member, a spring motor, connections between said motor and shaft, means operable independently of the movement of said gyroscope locking member for setting and locking said 30 motor, and means operable from the exterior of the torpedo for releasing said spring motor locking means.

5. In a gyroscopically controlled torpedo, the combination with a gyroscope, of a member 35 movable to and from a position to lock said gyroscope, a rotary shaft for controlling said locking member, a pinion rotatably mounted on said shaft, a connection between said shaft and pinion permitting a limited

independent movement of either of said members, a motor geared to said pinion, and means operable from the exterior of the torpedo for setting said motor in operation.

6. In a gyroscopically controlled torpedo, the combination with a gyroscope, of a member 45 movable to and from a position to lock said gyroscope, a rotary shaft for controlling said locking member, a pinion rotatably mounted on said shaft, a slotted connection between said shaft and pinion permitting a 50 limited independent movement of either of said members, a spring motor geared to said pinion, a lock to restrain the operation of said motor, and means operable from the exterior of the torpedo for releasing said last 55 named lock.

7. In a gyroscopically controlled torpedo, the combination with a gyroscope, of a member movable to and from a position to lock said gyroscope, a rotary shaft for controlling 60 said locking member, a pinion rotatably mounted on said shaft and provided with a slot, an arm secured to said shaft and extending into said slot for engagement by the pinion, a spring motor for turning said 65 pinion in one direction, a reciprocatory rack meshing with said pinion, a spring pressed pawl for holding said rack in one position against the tension of the spring motor acting through said pinion, and means operable from the exterior of the torpedo for 70 releasing said pawl.

In testimony whereof I have hereunto set my hand.

HAROLD W. SHONNARD.
